UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

BOTTOM LIFTING AND EQUALIZING MECHANISM FOR ROAD GRADERS.

Application filed October 25, 1927. Serial No. 228,673.

This invention comprehends certain new and useful improvements in road grading machines, and relates especially to certain improvements in the bottom lifting and equalizing mechanism such as I have disclosed in my previous Patent No. 1,551,629, dated September 1, 1925.

In the patent above mentioned, as will more fully appear by a reference to the specifications, claims, and drawings thereof, means are provided for equalizing the heavy weight of the "circle" and mold board whereby the operation of tilting the mold board with one end lower than the other, or of bodily lifting the mold board to an elevated position, is made easy, this patented construction comprising a supporting frame, a "bottom," i. e., draw bars, circle, and mold board, and means on the supporting frame under the easy control of the operator for vertically moving the bottom, springs being provided to counterbalance and exert a lifting force upon the grader bottom, and the parts being so constructed and arranged that the lifting force of said springs is equalized in all positions of the grader bottom. That is to say, the parts are so constructed and arranged that no more effort is required to lift or cant the heavy bottom than is necessary to lower the same, the whole mechanism being under the manual control of the operator on the grader platform, and being capable of speedy accomplishment.

The present invention has for its object to improve the construction and more especially the arrangement of the parts of this patented bottom lifting and equalizing mechanism above identified, and more especially to so arrange the parts that they will in no wise interfere with the vision of the operator in watching the work as it progresses and in keeping his machine under perfect control.

With these and other objects in view, as will more fully appear as the description proceeds, reference is to be had to the following description and accompanying drawings, in which

Figure 1 is a side elevation of so much 50 of a road grading machine as is necessary to illustrate the present invention, parts being shown in section;

Fig. 2 is a top plan view of parts in section in Fig. 3, and 55

Fig. 3 is a detail view of one of the sectors 28 as hereinafter referred to.

In the accompanying drawings, I have illustrated only such portions of a road grader as will be necessary to enable those 60 skilled in the art to which this invention appertains to understand the present invention, and in the drawings, the numeral 10 designates the main arched frame bars of the grader, 11 one of the draw bars, 12 the 65 "circle" as it is called, and 13 the mold board or scraper, these parts 11, 12, and 13, and their concomitant parts constituting what is herein referred to as the "bottom" 70 of the machine which is designed to be raised and lowered by the lifting and equalizing mechanism of the present invention.

Carried by the frame bars 10 of the grader are bearing brackets 14 extending laterally in opposite directions, as best illustrated in Fig. 2, and constituting forward bearings for the longitudinally extending lift shafts 15 which extend parallel to the frame bars 10 and are provided at their forward ends with crank arms 16 which are 75 pivotally connected with the bottom by means of vertically disposed links 17, as shown. The rear ends of the lift shafts 15 have mounted thereon worm gears 18 meshing with worms 20 on shafts 21 that are provided with the usual hand wheels 22 in convenient proximity to the operator's station or platform 23 at or near the rear of the grader. 80

Intermediate their ends the lift shafts 15 are provided with beveled gears 24 which mesh with corresponding gears 25 on transversely extending shafts 26, said shafts 26 being suitably supported by means of bearing brackets 27. 90

The shafts 26 are mounted for independent movement, as of course are the lift shafts 15 which operate them, and each shaft 26 95

has secured to it an approximately sector-shaped member 28 which is preferably provided with a groove 29 in its edge face. These members 28 constitute weight equalizers, and it will be seen that each member, as in the construction of my former Patent No. 1,551,629, hereinbefore mentioned, comprises a radially extending arm 30, and that the sector-shaped portion of the member 10 starts from a point relatively adjacent the center of motion of the member, extends out tangentially to a circle concentric to the center of motion, as at 31, and then extends at an angle, this portion 32 being in turn tangential to a circle concentric to the center of motion and then extends approximately concentrically, as at 33, to said center of motion and joins the extremity of the arm.

Pivotedly connected or shackled to the eye 20 34 in the extremity of the arm 30, is a chain 35 or other flexible element, said chain extending longitudinally forward from the sector-shaped member, as shown, and being suitably connected at its forward end to an 25 equalizing spring 36 which may be either a compression spring or an expansion spring, or a plurality of sections of expansion springs, so long as it exerts a pull upon the chain 35 in a direction to swing the 30 sector-shaped member 28 in a direction to turn its corresponding shaft 26, and the corresponding lift shaft 15, through the instrumentality of the beveled gears 24 and 25 to exert a lifting force upon the correspond- 35 ing crank arm 16, the links 17, and the bottom or that portion of the bottom to which the corresponding links are connected. The forward end of each spring 36 is connected by means of a shackle or tie-bolt 37 to a 40 transversely extending bar 38 suitably supported upon the frame bars 10, the bolts 37 being preferably eye-bolts as shown, and being held adjustably in position by means of nuts 39. Preferably the springs are 45 encased in tubular housings or sleeves 40.

From the foregoing description in connection with the accompanying drawings, it will be understood that in the operation of lifting or lowering the bottom the operator 50 on the platform 23 will turn one or both of the hand wheels 22 in the required direction as desired, which will result in turning the shaft or shafts 15 and raising or lowering the crank arm 16 according as it is desired 55 to raise or lower either or both sides or ends of the mold board.

In the rotation of the shaft or shafts 15, it is obvious that by means of the intermeshing beveled pinions 24 and 25, the corresponding shaft or shafts 26 will also be turned, the sector-shaped members 28 being moved to increase the tension upon the springs 26, or to allow that tension to relax.

It is to be particularly noted, as brought 60 out more in detail in connection with my

former Patent No. 1,551,629, that in this movement of the parts, when the springs relax in their tension, the leverage increases, and when the tension upon the springs increases, the leverage decreases whereby the 70 weight of the parts to be lifted is equalized at all times in all positions of the lifted member or bottom, and there is no sudden lifting and then a very great strain on the mechanism, the lift being gradual because 75 as the work to be done increases the action of the spring increases.

With the ordinary grader, especially of the heavy duty type, it takes considerable effort to lift the blade and its attached parts, 80 but with this spring lift and evener or equalizer, the hand wheels 22 may be operated very readily in either direction at increased speed and with much greater ease.

What is claimed, is:

1. In a road grader, a supporting framework, a bottom, equalizing mechanism for raising said bottom and permitting the same to lower, said mechanism comprising longitudinally extending lift shafts supported by 90 the framework and operatively connected to the bottom, independently movable transverse shafts mounted on the framework and having beveled gear connections with the first named shafts, springs extending longitudinally of the framework, and connections between the second named shafts and said springs adapted to equalize the lifting force exerted by said springs in all positions of the bottom.

2. In a road grader, a supporting framework, a bottom, and a lifting mechanism for the bottom, said lifting mechanism comprising longitudinally extending shafts supported by the framework and operatively connected to the bottom, transverse shafts also supported by the framework between the first named shafts and operatively connected to the first named shafts to turn therewith, springs extending longitudinally of 105 the framework, cables connected at one end to said springs, and sector-shaped members carried by the second named shafts and connected to the other ends of said cables respectively, said sector-shaped members being 110 designed to have the cables partially wind thereon when the second named shafts are turned, and of such shape that they will equalize the lifting force exerted by the 115 springs in all positions of the bottom.

3. In a road grader, a supporting framework, a bottom, and a lifting mechanism for the bottom, said lifting mechanism including a cross-bar secured to the framework, longitudinally disposed springs connected at 125 one end to said cross-bar, cables connected to the other ends of said springs, sector-shaped members upon which said cables are adapted to partially wind, transverse shafts supported by the framework and carrying 130

said sector-shaped members, beveled pinions on the outer ends of said shafts, lift shafts extending longitudinally of the framework and provided with beveled gears meshing with the first named beveled gears respectively, said second named shafts being provided at their forward ends with crank arms

operatively connected to the bottom, and manually operable means at the rear ends of the second named shafts for rotating the latter.

In testimony whereof I affix my signature.

FRANKLIN E. ARNDT.
